(57) **CLAIM**

The ornamental design for an electronic controller and hydraulic valve block assembly, as shown and described.

DESCRIPTION

In a preferred embodiment, the nature of this product is as a housing for an electronic controller primarily useful for containing an electronic circuit that forms a controller for operating a machine, and in particular for controlling valves that operate hydraulic actuators.

FIG. 1 is a downward perspective view from a right front corner of an electronic controller and hydraulic valve block assembly embodying the new design;

FIG. 2 is an upward perspective view from a left rear corner thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a left side elevational view thereof; and,

FIG. 8 is a right side elevational view thereof.
